UNITED STATES PATENT OFFICE.

EDWARD SAMUEL, OF PHILADELPHIA, PENNSYLVANIA, ASSIGNOR TO WILLIAM WHARTON, JR., AND COMPANY, (INCORPORATED,) OF SAME PLACE.

PERMANENT WAY OF RAILWAYS.

SPECIFICATION forming part of Letters Patent No. 366,031, dated July 5, 1887.

Application filed April 23, 1887. Serial No. 235,877. (No model.)

To all whom it may concern:

Be it known that I, EDWARD SAMUEL, a citizen of the United States, and a resident of Philadelphia, Pennsylvania, have invented 5 certain Improvements in Permanent Ways of Railways, of which the following is a specification.

One object of my invention is to so connect railroad-chairs to their supports that they 10 may be adjusted thereon, but when secured will be firmly locked in place, a further object being to deaden the noise caused when a metal chair and a metal support therefor are secured together in contact with each other.

15 In the accompanying drawings, Figure 1 is a transverse section of a conduit-railway structure, illustrating my improvement. Fig. 2 is a perspective view of a chair, part of the support and filling-piece detached. Fig. 3 is 20 a side view, partly in section, showing the positions of the parts before the chair is secured to the support. Fig. 4 is a similar view showing the parts after the chair has been secured, and Fig. 5 is a view showing the chair 25 secured to a wooden cross-tie.

In Fig. 1 I have shown an electrical or cable conduit, with arms A A, which support the rails and act as cross-ties, although it should be understood that any cross-tie or 30 base-plate may be used in carrying out my invention. The arm A has a plate, a, on which rests the chair B, the latter having a base, b, corresponding to the supporting-plate a, and a vertical standard, c, to which is secured the 35 web d of the rail D.

In the under side of the base-plate b of the chair B are grooves e e—two in the present instance—extending parallel with the rail or transversely to the line of lateral thrust on 40 the chair, and in the upper face of the supporting-plate a of the arm A are grooves f f, preferably located directly beneath the grooves in the under side of the chair B.

Between the base-plate of the chair and the 45 supporting-plate a is inserted a slab, E, of wood, lead, rubber, or other elastic, semi-elastic, or flexible material, which acts as described hereinafter, to form both a chair-lock and a sound-deadener.

50 The base-plate of the chair, the supporting-

plate a, and the slab or filling-piece E are provided with openings through which securing-bolts i i are passed, the openings in the plate a or in the base-plate b being elongated in order that the chair may be adjusted laterally in 55 respect to the support. When the parts are in the positions shown in Fig. 3, the bolts are loose and the chair is not secured in position, but is free to be adjusted in order that the track may have the proper gage. When the 60 chair has been properly adjusted, however, the nuts on the bolts i are screwed tight, and pressure is thus exerted upon the material of which the filling-piece E is made, and, owing to the character of this material, it will be 65 forced into the grooves e and f of the supporting-plate a and base-plate b, and firmly lock them together, so far as regards lateral motion of one upon the other, while at the same time it tends to exert upon the nuts a pressure 70 which will prevent them from being loosened, and it acts as an absorbent of sound and serves as a cushion between the chair and its supporting-plate.

In Fig. 5 I have shown the chair and filling-piece used with a grooved wooden cross-tie. 75 In this case spikes may be used instead of bolts; but the latter are preferred.

I claim as my invention—

1. The combination of the support having 80 grooves in its upper surface, the chair having grooves in its under surface, and an interposed filling-piece, E, adapted to be forced into the grooves when the chair is secured to the support, all substantially as set forth. 85

2. The combination of the support having grooves in its upper surface, a chair having grooves in its under surface, an interposed filling-piece, and securing-bolts adapted to openings in said support and chair, the openings in one of said parts being elongated, all substantially as specified. 90

In testimony whereof I have signed my name to this specification in the presence of two subscribing witnesses.

EDWD. SAMUEL.
